United States Patent Office

Des. 225,480

Patented Dec. 12, 1972

225,480

GARMENT BAG

Sidney Annis, 16 W. 16th St., New York, N.Y. 10011

Filed Mar. 8, 1971, Ser. No. 122,277

Term of patent 14 years

Int. Cl. D3—99

U.S. Cl. D87—1

FIG. 1 is a front elevational view of a garment bag showing my new design;

FIG. 2 is a side elevational view of the garment bag shown in FIG. 1 as seen from the right thereof;

FIG. 3 is a top plan view thereof;

FIG. 4 is a bottom plan view thereof; and

FIG. 5 is a reduced rear elevational view thereof.

I claim:

The ornamental design for a garment bag, substantially as shown.
